UNITED STATES PATENT OFFICE.

GEORGE PETER EASTMAN, OF TORONTO, CANADA.

DESIGN FOR A FRAME FOR ELECTRICALLY-OPERATED CLOTH-CUTTERS.

SPECIFICATION forming part of Design No. 29,000, dated July 5, 1898.

Application filed April 26, 1898. Serial No. 678,919. Term of patent 7 years.

To all whom it may concern:

Be it known that I, GEORGE PETER EASTMAN, a subject of the Queen of Great Britain, and a resident of the city of Toronto, in the county of York, in the Province of Ontario, Canada, have invented a new and original Design for a Frame for Electrically-Operated Cloth-Cutters, of which the following is a specification, reference being had to the accompanying drawings, forming part thereof.

The drawings represent in Figure 1 a perspective view of the frame, showing my design therefor. Fig. 2 is a section through the standard.

The leading feature of my design consists of a base-plate with beveled edges and upwardly-extending stem affixed thereto and provided with a rearwardly-extending support, the motor field-magnets such as shown held thereon, and a knife-rod support and guide in the form shown.

A is the base-plate, which is provided with the beveled edge *a*.

B is the stem, which is triangular in form, as shown, and has a rearwardly-extending flat projection *b*.

C are the motor field-magnets in ring form, secured on the back of the projection *b*.

D is a loop-shaped journal-casting connected to the front bar D' of the motor.

E is an arm extending upwardly from the top of the front bar D' and having the vertical journal *e*.

What I claim is—

The design for a frame for an electrically-operated cloth-cutter herein shown and described.

GEORGE PETER EASTMAN.
